By Jas. L. Shidmore,
his Attorney,

UNITED STATES PATENT OFFICE.

DOMINICK A. REAGAN, OF ALTOONA, PENNSYLVANIA, ASSIGNOR OF ONE-THIRD TO FREDERICK HESSER, OF ALTOONA, PENNSYLVANIA.

DEVICE FOR AUTOMATICALLY OPERATING FIRE-DOORS.

SPECIFICATION forming part of Letters Patent No. 783,891, dated February 28, 1905.

Application filed September 19, 1904. Serial No. 225,094.

To all whom it may concern:

Be it known that I, DOMINICK A. REAGAN, a citizen of the United States, residing at Altoona, in the county of Blair and State of Pennsylvania, have invented new and useful Improvements in Devices for Automatically Operating Fire-Doors, of which the following is a specification.

This invention relates to automatically-operated fire-doors; and one of the objects of the same is to provide means for automatically opening and closing the fire-door of a fire-box of steam-boilers for the purpose of admitting air and to permit the fireman to feed coal under the boiler.

Another object is to provide means for automatically opening and closing the fire-door of a locomotive at stated intervals of time to permit the fireman to shovel in coal without opening the fire-door by hand and at the same time to admit the necessary inflow of air to the fire to secure the most economical consumption of fuel, a most complete combustion, and a material reduction in the labor of firing.

Owing to the increase in size and capacity of locomotives in recent years and the consequent increase in consumption of fuel and the extra labor required in keeping the fire in such condition that the steam-pressure may be constant, it is found very necessary that some means be resorted to for aiding the fireman to perform his service without loss of fuel. It has become a difficult matter for one man to keep the fire-box in proper condition under all circumstances, and owing to the length of time the fire-door is usually left open by the old practice bad results occur, such as loss of fuel, owing to the fact that there is a constant rush of cold air over the fire, and this results in a sudden contraction of the boiler-plates, which injures them and breaks the stay-bolts.

A fire-door that is automatically opened and closed at short intervals not only feeds the required amount of air to properly support combustion, but gives the fireman an opportunity to get the coal and shovel it on without interference and saves fuel that would otherwise be carried away in smoke and unconsumed

particles, owing to a constant rush of cold air in an open door. These and other objections are overcome by means of my invention.

In the accompanying drawings I have shown one of the means which I may employ for intermittently opening and closing the fire-door of a furnace; but I may use other devices for accomplishing the purpose.

In said drawings, Figure 1 is a rear elevation of a locomotive steam-boiler, showing a fire-door and a motor for intermittently opening it. Fig. 2 is a view of the motor with the face-plate removed and showing the valve, the piston, and other internal parts. Fig. 3 is an exterior face view of the motor.

Referring to the drawings for a more particular description of my invention, the numeral 1 designates the rear end of a locomotive steam-boiler, and 2 is the fire-door thereof. As shown in Fig. 1, the fire-door is mounted to slide vertically in a guideway comprising keepers 3. At the upper edge of the door a drive-chain 4 is connected, said drive-chain passing up and over a small idler sprocket-wheel 5, journaled on a stub-shaft 6, secured to the back of the boiler 1. From the sprocket-wheel 5 the drive-chain passes around under a large sprocket-wheel 7, and the end of the chain is secured at a suitable point to said sprocket-wheel 7, as at 8. Any suitable means may be employed for partially rotating the sprocket-wheel 7 and then permitting the weight of the fire-door to return it to its original position, and thus close the fire-door, or I may resort to other means for accomplishing this result and dispense with the sprocket-wheels and chain.

The motor which I have shown and I may employ comprises a casing 9 of circular or cylindrical contour. This casing may be comparatively narrow from front to rear and may be connected to the rear plate of the boiler, as shown. Inside the casing, as shown in Fig. 2, is an abutment or partition 10, which divides the interior into two compartments 11 12. A small inlet-pipe 13 communicates through the wall of the casing with an oscillating valve 14, mounted to partially rotate

upon a shaft 15 and provided with an opening 16, which is alternately brought into coincidence with the inlet-opening 17 for the admission of live steam to the interior of the 5 valve 14. This valve 14 is reciprocated or oscillated from the admission-port 17 to a discharge-port 18, leading into the compartment 12, the valve having a steam-tight surface bearing against the abutment or partition 10 at 19 and 20. A piston 21 is fitted to a sleeve 22, journaled on a central bearing 23, and this piston is adapted to be forced by the steam from the valve 14 from its upper position to a point just beyond the exhaust-port 24, when 15 the weight of the fire-door 2 will return the piston to its original or upper position, owing to the fact that the live steam is passed out through said exhaust-opening 24. To carry the valve 14 back to a position to receive a 20 new supply of steam from the port 17, an arm 25 is secured to or formed on the sleeve 22 outside the face-plate 26 of the casing 9. A similar arm 27 projects from the sleeve 22^a of the valve 14. Tappets 28 29 are also formed 25 on or secured to the sleeves 22 and 22^a. Pivoted to the arm 27 is a cut-off rod 30, said rod passing through a slotted hub 31 on the arm 25. Spring-stops 32 and 33 are adjustably secured to the cut-off rod 30. When the tappets 28 29 are carried into contact by the 30 movement of the piston 21 in its downward stroke, the valve-opening 16 is carried to the inlet-port 17 by the further movement of said piston. When the valve-opening 16 has 35 arrived at the inlet-port 17, the spring-stop 32 is brought into contact with the slotted hub 31 of the arm 25, and thus the valve-opening 16 is prevented from passing by the inlet-port 17. When the valve-opening has 40 established communication with the inlet-port 17 and the stop 32 has come in contact with the slotted hub 31, the piston 21 has just passed the exhaust-port 24 and the tappet 29 has been carried by the tappet 28. The purpose 45 of the spring-stop 32 is to limit the rotation of the valve 14 beyond the point of communication of the opening 16 and the inlet 17. After the piston passes the exhaust-port 24 the weight of the fire-door 2 returns the 50 piston to its upper position, and the tappets 28 29 move the valve 14 to its discharge position. The curved faces of the tappets 28 29 are brought into contact by the weight of the fire-door, and they pass each other. The further upward movement of the piston 21 carries the arm 25 and the slotted hub 31 down until the latter is in contact with the spring-stop 33, and this stop prevents the upward 55 impetus of the piston 21 from giving a forcible stroke or blow of said piston against the valve 14. Thus the cut-off rod 30 and the spring-stops 32 33 serve to limit the rotation of the valve 14 beyond its point of communication with the inlet-port 17 and to also serve 60 as a buffer for the return stroke of the piston. 65

Hinged to the lower edge of the fire-door is a small stoke-door which may be opened by hand when desired to rake the fire.

If desired, the door may be provided with a series of small holes or openings, as shown 70 in Fig. 1 of the drawings, for the admission of air and serving to prevent the burning away of the door, dispensing with the use of the usual lining placed on the inside of the door and increasing its life and durability. 75

The operation of my invention will be understood from the foregoing.

Various changes in form and details may be resorted to without departing from the spirit or scope of my invention and other means for 80 opening and closing the fire-door may be resorted to should the automatic means for any reason become inoperative.

It is to be noted that the fire-door is opened and closed at short intervals of time and that 85 fresh air is fed into the fire-box at such periods as will increase combustion, while fresh supplies of coal may be fed in at any time.

If desired, a suitable signaling device can be utilized in connection with my improvements 90 for the purpose of warning the fireman that the door has started to open, thus determining the most convenient time for delivering the coal to the combustion-chamber.

Having thus described my invention, what 95 I desire to secure by Letters Patent and claim is—

1. A steam-boiler furnace provided with a fire-door, and means for automatically opening 100 said door at intervals.

2. A fire-box door provided with means for automatically opening the same at predetermined intervals of time, and means for permitting the door to close by gravity.

3. In a device of the character described, a 105 fire-door mounted to slide in a guideway, a motor connected to the door and operated to slide the door in the guideway to automatically open it at predetermined intervals, and means to permit the door to close by gravity. 110

4. In a device of the character described, a fire-door, a motor, a flexible connection between the door and motor, and means whereby 115 said motor is operated to automatically open the door at predetermined intervals of time, and means to permit said door to close by gravity.

5. In a device of the character described, a fire-door mounted in a vertical guideway, a motor having an oscillating piston, a sprocket-wheel on the piston-shaft, a drive-chain connected to the door and to the sprocket-wheel, and means for oscillating the piston. 120

6. In a device for opening and closing fire-doors automatically at predetermined intervals, a motor comprising a casing, a piston therein, an abutment in said casing, an oscillating valve, and means for opening the same within said casing, and a connection between the motor and the fire-door. 125 130

7. In a device of the character described, a motor, comprising a casing, a piston in the casing, an inlet-port, an exhaust-port, an oscillating valve adapted to contain live steam and carry it from the inlet-port to a discharge-orifice in front of the piston, a cut-off rod, and tappets controlled by said cut-off rod for returning the valve to its original position, one of said tappets being moved by the piston, and connections between the fire-door and the motor, whereby the fire-door is automatically

opened at intervals and permitted to close by gravity.

8. A fire-door provided with means for automatically opening the same at predetermined intervals and permitting it to close by gravity, and a small auxiliary door hinged to the lower edge of said fire-door. 15
